WIRELESS DIRECTION FINDING SYSTEM

Harry Melville Dowsett, Winchmore Hill, London, and Louis Edward Quintrell Walker, Maida Vale, London, England, assignors to Radio Corporation of America, a corporation of Delaware

Application March 20, 1934, Serial No. 716,474
In Great Britain March 31, 1933

3 Claims. (Cl. 250—11)

This invention relates to wireless direction finding and navigation systems and has for its object to provide an improved system wherein direction finding operations can be satisfactorily 5 accomplished by relatively unskilled persons.

In wireless direction finding and navigation systems at present in common use a fixed (shore) transmitting station transmits Morse or other code signals which are picked up by mobile receivers (ships) and serve to identify said station. Information as to the direction or bearing of said station is obtained at the receiver in any of a variety of well known ways—e. g. where the transmitter is omnidirectional, by means of a 10 rotatable frame aerial or radiogoniometer search coil at said receiver. By reason of the use of the Morse or equivalent code, skilled operators are required for such systems and the present invention provides an improved system wherein 15 the need for such operators is avoided by replacing the code signals by what are commonly called "video" signals, because the modulation impulses thereof are representative of light and dark elemental areas of a scanned picture. The transmitters in our system are caused to send 20 television pictures of their identification names and pictures of directional indications. The receivers, on the other hand, are fitted with television picture reconstructing devices.

The main object of this invention is to provide 25 an improved television bearing finding or navigation system wherein synchronism between the transmitting and receiving television scanning devices shall be maintained and shall not be liable to be lost as a result of variations in 30 received signal strength consequent upon the operation of bearing finding.

As will be seen later herein, the invention provides a system wherein proper synchronism is 35 maintained between transmitting and receiving scanning devices and wherein no skilled operators are required at the receiver at all, the receiver being of the omni-directional type.

According to this invention a wireless transmitting station for use for direction finding and navigation purposes transmits continuously a characteristic picture which may consist of or include the identification name of the station. The device comprises two frame aerials which 45 are arranged at right angles to one another and are continuously rotated. One of these frame aerials is energized with a carrier frequency modulated with the television signal plus a synchronizing signal and the other is energized by the 50 carrier frequency modulated with the synchroniz-

nizing signal only. The two carriers may be of the same frequency and derived from a common driving source. The polar diagram resulting from a transmitting arrangement in accordance with this invention and so far as the synchronizing signal modulated energy is concerned will be a circle, or a close approximation thereto, and hence the receiving station (which has an omni-directional antenna) will pick up a substantially constant synchronizing signal strength independent of the bearing of the transmitting station relative thereto. On the other hand, however, the polar diagram of transmission so far as the television signal modulated energy is concerned, will be a rotating figure-of-eight diagram.

The nature of my invention and one manner in which the same may be carried out has been illustrated in the drawing, in which:

Fig. 1 shows diagrammatically the essential features of a transmitting system arranged in accordance with my invention;

Fig. 2 illustrates details of aerials of the directive type which may be used in the system in Fig. 1; while

Fig. 3 illustrates by curves the nature of the various fields produced and the manner in which the same are modulated.

A convenient particular arrangement of transmitting apparatus in accordance with this invention is illustrated in Figures 1 and 2 of the accompanying drawing and comprises a source 1 of synchronizing signals whose output is suitably amplified by a low frequency amplifier 2 and then applied to a modulator 3 which modulates as an intermediate amplifier 5 a local oscillation frequency derived from a source 4 of local oscillations, the resultant modulated carrier wave being further amplified as necessary at 6 and radiated from one (frame B) of two mutually perpendicular frame aerials A and B (shown in Figure 2) which are mounted to rotate together. The aerials are preferably mounted on a rotatable shaft as indicated conventionally in Fig. 2 by the arrow surrounding said shaft. Rotation may also be had by means of a continuously driven motor (not shown). The transmitting apparatus also comprises a source 7 of characteristic television signals which are amplified and combined at 9 with synchronizing signals obtained, after further amplification at 8, if required, from the synchronizing signal generator or (as shown) from the amplifier 2 energized therefrom. Means (not shown) are preferably provided for adjusting the phase and amplitude relations between the television and synchroniz-

ing signals before mixing them at 9. The mixed signals are fed to a modulator 10 which modulates in an intermediate amplifier 16 an oscillation frequency either derived from the source 4 or (as illustrated) from a separate source 12 synchronized with source 4. The resultant modulated carrier, after such further amplification at 13, as may be necessary, is impressed upon the second A of the mutually perpendicular frames.

Means should, of course, be provided to enable the officers at the receiving station to learn the direction of the transmitting station as a result of the reception of energy in the rotating figure-of-eight transmission. Preferably this is accomplished after the manner set forth in British Patent No. 400,279 by modulating the energy in the rotating figure-of-eight transmission with television signals giving, in addition to an indication identifying the transmitting station, an indication of the direction of the rotating beam at any instant. Thus, for example, the picture transmitted on the rotating beam may consist in part of a picture of the name of the transmitting station and in part of a portion of a compass card, said portion, of course, continuously changing as the beam rotates.

The general nature of the polar diagrams resulting from a transmitter as shown in Figures 1 and 2 is illustrated in the accompanying Figure 3. In Figure 3 the circle SS is the polar diagram of radiation as regards the synchronizing signals, this circle being the summation of the two figure-of-eight diagrams a and b. The television signal polar diagram will, of course, be the diagram a, since only frame A radiates the television signals. a is the diagram of frame A and b the diagram of frame B.

It will be seen that the present invention provides an arrangement wherein a compact frame aerial system may be employed, and wherein the desired phase and amplitude relations of the radiated waves carrying the television and synchronizing signals may be easily obtained so that the synchronizing signal transmission does not adversely affect the effective directivity of the other transmission.

Having now particularly described and ascertained the nature of our said invention and in what manner the same is to be performed we declare that what we claim is:—

1. In a wireless transmitting station for use for direction finding, television apparatus for transmitting television signals representative of a characteristic subject, including a directional indication, means for transmitting accompanying signals for synchronization, a plurality of directive antenna systems the directivity of which may be varied according to variations in the directional indications to be transmitted, means for energizing one of said antenna systems with carrier energy modulated with the television signals, a source of synchronizing signals, and means for energizing all of the said directive systems with carrier energy modulated with said synchronizing signals. 5

2. In a directional indicating radio beacon system, means including a plurality of variably directive antennae for radiating modulated signals, means for so varying the significance of the modulated signals in accordance with the directive effect of one of said antennae as to produce distinctive indications appropriate to each direction, means including a panoramic picture to be scanned synchronously with the rotation of the directive effect of that one of said antennae previously mentioned whereby the modulated signals may be composed, and means for generating and for simultaneously radiating from both said antennae non-directional synchronizing signals whereby a television receiver may be maintained operative to reconstruct said distinctive directional indications. 10

3. In a radio beacon system, a pair of loop antennae having a common vertical axis of rotation and maintained in mutually perpendicular planes, means for continuously rotating said antennae about said axis, a source of carrier frequency energy, means including a source of synchronizing signals for modulating said carrier frequency energy, means for amplifying the energy so modulated and for causing both said antennae to radiate said energy simultaneously, a source of television signals, means for causing said television signals to be applied as additional modulations of the energy radiated from one only of said antennae, and means for characterizing said television signals in accordance with variations in the directivity of the antenna to which they are applied. 15
